UNITED STATES PATENT OFFICE.

GEORGE EDWIN BILL AND ALBERT DEWEEZE REDMAN, SR., OF HARRISBURG,
PENNSYLVANIA.

SECTIONAL INCANDESCENT LAMP.

No. 860,627.

Specification of Letters Patent.

Patented July 23, 1907.

Application filed January 30, 1906. Serial No. 298,659.

To all whom it may concern:

Be it known that we, GEORGE EDWIN BILL and ALBERT DEWEEZE REDMAN, Sr., citizens of the United States, residing, respectively, at 255 and 263 Northstreet, 5 Harrisburg, in the county of Dauphin and State of Pennsylvania, have invented a new and useful Sectional Incandescent Lamp, of which the following is a specification.

This invention relates to socket controllers for incandescent lamps and has for its object to provide means for varying the intensity of the light by the movement of the controller.

A further object of the invention is to provide an incandescent lamp having a plurality of filaments adapted to be successively thrown into circuit to produce lights of different candle power.

A further object is to provide a plurality of spring contact fingers movable to operative position through the medium of a disk or plate, the latter being provided 20 with a cam face having a series of spaced recesses or depressions formed therein for locking the contact fingers in circuit closing position.

A still further object is to generally improve this class of devices so as to add to their utility and durability as well as to reduce the cost of manufacture.

Further objects and advantages will appear in the following description, it being understood that various changes in form, proportions and general assemblage of parts may be resorted to within the scope of the 30 appended claims.

In the accompanying drawings forming a part of this specification:—Figure 1 is a side elevation partly in section of an incandescent lamp provided with a socket controller or regulator constructed in accordance with 35 our invention. Fig. 2 is a transverse sectional view taken on the line 2—2 of Fig. 1. Fig. 3 is a detail sectional view showing in elevation the operating cam or disk in position to engage the contact fingers. Fig. 4 is a similar view showing one of the contact fingers 40 locked in circuit closing position. Fig. 5 is a side elevation partly in section illustrating a modified form of the invention. Fig. 6 is a transverse sectional view taken on the line 6—6 of Fig. 5.

Similar numerals of reference indicate corresponding 45 parts in all the figures of the drawings.

The device consists of a vacuum globe or bulb 5 depending from a metal cap 6 and secured in position by a plug or matrix of plaster-of-paris, porcelain or other suitable insulating material 7. Disposed within the 50 bulb 5 are a plurality of filaments 8 each connected by a conductor 9 to a stationary contact 10 embedded in the plug 7, one of the wires 9 being soldered or otherwise secured to the metal cap 6, as shown at 11.

Rigidly secured to the plug 7 is one end of a rod or

pin 12 the opposite end of which is free to revolve in a 55 tubular casing or sleeve 13 secured to and depending from a mating cap 14, the latter being provided with a lug or projection 15 adapted to engage a segmental slot or groove 17 in the cap 6 whereby the caps are locked against accidental displacement. 60

The cap 14 is formed with terminal threads 18 adapted to engage the corresponding threads 19 of an ordinary incandescent lamp socket 20 so that the device may be conveniently connected in a lighting circuit, one terminal of the circuit being connected to 65 the cap 14 and the opposite terminal to the metal casing or sleeve 13.

Secured to the rod 12 are a plurality of laterally extending spring contact fingers 21 adapted to engage the contacts 10 and thereby close the circuit through 70 any one of the filaments 8 so as to produce lights of different candle power.

The contact fingers are moved to operative position through the medium of a plate or disk 22 secured to or formed integral with the sleeve 13 and provided with 75 a cam face 23 adapted to successively engage and depress the fingers when either the cap 6 or the cap 14 is partially rotated.

The active face of the operating cam is formed with a series of spaced notches or recesses 24 adapted to receive the contact fingers when the latter are moved to operative position and thereby lock said fingers in positive contact with the terminals of the filaments. 80

When it is desired to vary the intensity of the light, the bulb is grasped in the hand and partially rotated 85 which causes the cap 6, carrying the rod 12 and fingers 21, to also rotate. As the fingers 21 come in contact with the cam face 23 of the plate 22 they are successively depressed or moved to operative position in engagement with the adjacent contacts 10 and in which 90 position they will enter the peripheral notches or recesses 24 so as to effectually lock said contact fingers against accidental rotation. It will thus be seen that when the plate 22 is rotated so as to cause the first spring finger to engage the adjacent contact 10 the 95 current will flow through the sleeve 13 and plate 22 to said contact and thence through the bank of loops or filaments 8 to the contact 11 and off to the line. When the plate 22 is again rotated the latter will engage and depress the second spring finger thereby cutting out 100 the first loop or filament and so on throughout the entire series of contacts, as will be readily understood. If desired, however, the bulb may be held stationary and the cap 14 revolved, the result accomplished being the same in both instances. 105

In Figs. 5 and 6 there is illustrated a modified form of the invention in which the contact fingers 21 are normally held in engagement with the contacts 10

and successively elevated or moved to inoperative position to cut out any particular filament by means of a spirally disposed operating member 25 secured to the sleeve 13' and having its free end deflected at 26 and 5 disposed in the path of movement of the contact fingers. In this form of the device as the fingers are successively elevated and held in inoperative position by engagement with the lower convolution of the operating member, as shown.

10 Having thus described the invention, what is claimed, is:—

1. A lamp having a plurality of filaments, stationary contacts connected to the filaments, movable contact members adapted to engage the stationary contacts, and 15 means for locking the movable contacts in circuit closing position.

2. A lamp having a plurality of filaments, stationary contacts connected to the filaments, movable contact members adapted to successively engage the stationary contacts for closing the circuit through any one of the filaments, and means for locking the movable contacts in 20 circuit closing position.

3. A lamp having a plurality of filaments, stationary contacts connected to the filaments, movable contact members adapted to engage the stationary contacts and an 25 operating cam for locking the movable contacts in circuit closing position.

4. A lamp having a plurality of filaments, stationary contacts connected to the filaments, yieldable contact members adapted to engage the stationary contacts, and an operating cam for depressing the movable contacts and locking the same in circuit closing position.

5. A lamp having a plurality of filaments, stationary contacts connected to the filaments, yieldable contact members adapted to engage the stationary contacts, and an operating cam for depressing the yieldable contacts, said cam having a plurality of spaced recesses formed in its active face for the reception of the yieldable contacts thereby to lock the same in circuit closing position.

40 6. A lamp having a cap and provided with a plurality of filaments, stationary contacts connected to the filaments, a rod carried by the cap and provided with radiating movable contact members adapted to engage the

stationary contacts, and means carried by the rod for locking the movable contacts in current closing position. 45

7. A lamp having a sectional cap and provided with a plurality of filaments, stationary contacts connected to the filaments, a rod secured to one of the cap sections and provided with yieldable contact members adapted to engage the stationary contacts, and means carried by the opposite cap section for depressing the movable contacts.

8. A lamp having a sectional cap and provided with a plurality of filaments, stationary contacts connected to the filaments, a sleeve carried by one of the cap sections, a rod secured to the opposite cap sections and seated in 55 said sleeve, yieldable contact members carried by the rod and adapted to engage the stationary contacts, and an operating cam carried by the sleeve for depressing the movable contacts and locking the same in circuit closing position.

9. A lamp having a sectional cap and provided with a plurality of filaments, stationary contacts connected to the filaments, a sleeve carried by one of the cap sections, a rod secured to the opposite section and seated in the sleeve, a plurality of spring contact fingers carried by the 65 rod and adapted to engage the stationary contacts, and an operating cam secured to the sleeve for successively depressing the contact fingers.

10. A lamp having a cap formed of a plurality of sections mounted for rotation and having interengaging parts, a plurality of filaments, stationary contacts connected to the filaments, a sleeve carried by one of the cap sections, a rod carried by the opposite cap sections and mounted for rotation in the sleeve, a plurality of spring contact fingers secured to and movable with the rod for 70 engagement with the stationary contacts, and a plate secured to the sleeve and having a cam surface adapted to depress the fingers in engagement with the stationary contacts, said cam surface being provided with spaced recesses for locking the fingers in circuit closing positions. 80

In testimony that we claim the foregoing as our own, we have hereto affixed our signatures in the presence of two witnesses.
